COIN REFILL MECHANISM

Ernest E. York, Portland, Maine, assignor to
 American Coin Changer Corp., Boston, Mass., a
 corporation of Maine

Application December 20, 1948, Serial No. 66,330

2 Claims. (Cl. 133—5)

1

This invention relates to apparatus for refilling the magazine of a coin changer automatically.

Where a coin-actuated machine is provided with a coin changer, it is necessary either to associate with the coin changer a magazine of substantial capacity or to provide means whereby the supply of coins in the magazine is continuously or intermittently replenished by diversion of coins accepted by the machine. As large capacity magazines are impracticable, the latter alternative is desirable, assuming the magazine refilling apparatus selected is capable of reliable and efficient operation and is not expensive to manufacture or difficult to service.

The apparatus of the invention meets fully the indicated requirements and is further advantageous in that it is adapted for use in both mechanically operated and electrically operated machines.

In accordance with the invention, each coin inserted into the machine which is of the same denomination as those the magazine is dimensioned to accommodate, is directed to the magazine, which may or may not receive it depending upon the level of the coins then in the magazine.

I shall particularly describe my invention with the aid of the accompanying drawings illustrating a preferred embodiment thereof which contemplates a machine dispensing an article of the value of five cents but which is adapted to be actuated with a ten cent piece or a twenty-five cent piece as well as with a five cent piece, one five cent piece being delivered with the purchase in the event of actuation of the machine with a ten cent piece, four five cent pieces being delivered with the purchase in the event of its actuation with a twenty-five cent piece.

In the drawings:

Fig. 1 is a view in elevation of the particular apparatus, the same being mounted within a box-like casing partly broken away to expose the apparatus;

Fig. 2 is an enlarged section along the lines 2—2 of Fig. 1; and

Fig. 3 is a section along the lines 3—3 of Fig. 2.

Referring to the drawings, the magazine 10 has an internal diameter slightly exceeding the diameter of a five cent piece and is mounted over a coin changer 11, comprising slides 12 and 14, supported by the floor of the casing 5. On actuation of slide 12, one five cent piece is released to a conduit 15 extending to a coin receptacle, not shown, accessible to the customer. When slide 14, which has a thickness corresponding to three five cent pieces, is actuated, it carries with it slide 12 to release a total of four five cent pieces

2

to the conduit. Such a coin changer is described in detail in my copending applications, Serial Numbers 719,007 and 56,569, filed December 28, 1946 and October 26, 1948, respectively.

5 Adjacent the magazine 10 and affixed to one wall of the casing 5 through flanges 16 is a vertically inclined coin chute 17 opening at its lower end to a coin box 18. Similarly secured to the same wall of the casing 5 through a flange 19 is a member 20 receiving five cent pieces from a coin classifier, indicated generally by the numeral 21 in Fig. 1, which is supplied with coins from chute 22 and which terminates in passageways 23, 24 and 25 (see Fig. 2). Ten cent pieces and twenty-five cent pieces, respectively, enter the chute 17 from the latter two passageways. The classifier may be of any suitable construction and, as it forms no part of the present invention, need not be described in detail here.

10 The flaring at 26 of the side walls of the member 20, the inlet of which is dimensioned in substantial correspondence with the dimensions of a five cent piece, facilitates entry of the coins. This member is cut out at 27 so that the passageway it provides opens both to the mouth of the magazine 10 and to a slideway 28 associated with chute 17, the chute having a port 29 therein immediately above the slideway. By reason of the shoulder 30, however, each coin received by the member is positively deflected toward the mouth of the magazine.

15 Member 20 and chute 17 may each be formed, with advantage, of sheet metal. In the particular arrangement shown, the open side of the chute is closed by the wall of the casing 5 to which the chute is secured.

20 Referring now particularly to Fig. 3 from which the operation of the described apparatus is apparent, it will be readily appreciated that when the level of the coins in the magazine is less than indicated in this figure coins delivered thereto immediately topple over on their faces, but that when the distance between that portion of the outlet of member 20 overlying the mouth of the magazine and the uppermost coin 45 in the magazine is less than the diameter of a five cent piece, the next coin delivered to the magazine is maintained on edge by the lowermost edges of the side walls of the member 20 coacting with the walls of the magazine which preclude edgewise movement of the coin. In such position the coin serves to deflect coins subsequently directed toward the mouth of the magazine by shoulder 30 onto the slideway 28 from which they pass through the port 29 into the chute 17. This condition is maintained until

such time as the height of the stack of the coins in the magazine is reduced through actuation of the coin changer 11.

Although the distance between the lower edges of the member 20 and the top of the magazine is not critical, it is manifestly desirable from the standpoint of proper operation of the apparatus, that the coin serving to deflect subsequent coins on to the slideway be held with its upper edges at least slightly above the top of the magazine. At all events, the coin on which the deflector coin rests should not be appreciably more distant from the top of the magazine than the diameter of the coins.

It is believed evident from the foregoing that the apparatus provide by my invention is quite inexpensive in construction and so simple in operation as to be substantially foolproof. The fact that coins of like value vary appreciably in thickness, does not interfere with the efficient and reliable operation of the apparatus, a feature of great practical importance.

It is understood that the invention will not be considered as restricted to the precise details of construction shown in the drawings, since various changes and modifications may obviously be made without departing from the scope of the invention or sacrificing the advantages derived from its use.

I claim:

1. Apparatus for refilling a vertically disposed cylindrical magazine associated with a coin changer which comprises a source of supply of coins accommodatable in the magazine, a vertically inclined chute adjacent the magazine having a side port therein and a slideway associated with said port, and a member providing a passageway between said source of supply and the mouth of the magazine having a downward outlet to said mouth and a lateral outlet to said slideway, said member further having side walls spaced apart a distance approximating the thickness of the coins and a shoulder serving to direct the coins towards said downward outlet, the ends of said side walls at the said downward outlet being spaced apart from the mouth of said magazine by a distance less than the diameter of the coins so that when the coins in the magazine

reach a predetermined level, not more distant from the said ends of said side walls than the diameter of the coins, the next coin entering the mouth of the magazine is maintained on edge by co-action of said side walls and the walls of the magazine in position to deflect subsequent coins through said lateral outlet on to said slideway and thence through said side port into said chute.

2. Apparatus for refilling a vertically disposed cylindrical magazine associated with a coin changer which comprises a source of supply of coins accommodatable in the magazine and a member providing a passageway between said source of supply and the mouth of the magazine having an outlet a portion of which overlies said mouth, said member further having side walls spaced apart a distance approximating the thickness of the coins and a shoulder serving to direct the coins toward that portion of the outlet overlying the ends of said mouth, said side walls overlying said mouth being spaced apart from the mouth of the magazine by a distance less than the diameter of the coins so that when the coins in the magazine reach a predetermined level, not more distant from the said ends of said side walls than the diameter of the coins, the next coin entering the mouth of the magazine is maintained on edge by co-action of said side walls and the walls of said magazine in position to deflect subsequent coins through that portion of the outlet which does not overlie said mouth.
